UNITED STATES PATENT OFFICE.

HERMANN C. STELLING, OF ORANGEBURGH, NEW YORK, ASSIGNOR TO THE OXWELD RAILROAD SERVICE COMPANY, A CORPORATION OF DELAWARE.

DESIGN FOR AN ACETYLENE LAMP.

Application filed April 5, 1926. Serial No. 17,181. Term of patent 14 years.

To all whom it may concern:

Be it known that I, HERMANN C. STELLING, a citizen of the United States, residing at Orangeburgh, in the county of Rockland and State of New York, have invented a new, original, and ornamental Design for an Acetylene Lamp, of which the following is a specification, reference being had to the accompanying drawing, forming a part of this application, wherein—

Fig. 1 is a side view, Fig. 2 is a front view and Fig. 3 is a top view of an acetylene lamp embodying the invention.

I claim:

The ornamental design for an acetylene lamp substantially as shown.

HERMANN C. STELLING.
